US0D1021770S

(12) **United States Design Patent** (10) **Patent No.:** **US D1,021,770 S**
(45) **Date of Patent:** **** Apr. 9, 2024**

(54) **POWER TOOL BATTERY CONVERTER**

(71) Applicant: **Vincent G. McIntosh**, Haines City, FL (US)

(72) Inventor: **Vincent G. McIntosh**, Haines City, FL (US)

(**) Term: **15 Years**

(21) Appl. No.: **29/829,187**

(22) Filed: **Mar. 3, 2022**

(51) **LOC (14) Cl.** **13-02**

(52) **U.S. Cl.**

USPC **D13/110**

(57) **CLAIM**

The ornamental design for a power tool battery converter, as shown and described.

DESCRIPTION

FIG. 1 is a front perspective view showing the top and right-side elevation view of a power tool battery converter, showing my new design;

FIG. 2 is a top plan view thereof;

FIG. 3 is a bottom plan view thereof;

FIG. 4 is a right-side elevation view thereof;

FIG. 5 is a left side elevation view thereof;

FIG. 6 is a front view thereof;

FIG. 7 is a rear view thereof; and,

FIG. 8 is a front perspective view similar to FIG. 1 showing the power tool battery converter being assembled between a power tool and a battery unit.

The dashed lines of a power tool and a battery unit shown in FIG. 8 form no part of the claimed design.

1 Claim, 5 Drawing Sheets
